UNITED STATES PATENT OFFICE.

PHILIPP WIRSCHING, OF SALEM, OHIO, ASSIGNOR TO THE WIRSCHING ORGAN COMPANY, OF SALEM, OHIO, A CORPORATION OF OHIO.

MUSICAL INSTRUMENT.

1,072,198.

Specification of Letters Patent.

Patented Sept. 2, 1913.

Application filed April 6, 1910. Serial No. 553,775.

To all whom it may concern:

Be it known that I, PHILIPP WIRSCHING, a citizen of the United States, residing at Salem, in the county of Columbiana and State of Ohio, have invented a certain new and useful Improvement in Musical Instruments, of which the following is a full, clear, and exact description, reference being had to the accompanying drawings.

10 My invention relates generally to musical instruments, the same being designed and arranged more particularly for use in connection with pipe organs that are adapted to be operated either manually or automatically.

Generally speaking, the object of the invention is the production of an organ having two or more manuals and novel coöperating parts so arranged that any particular 20 register of pipes in the organ may be played either manually or automatically, not only in the manual to which it may be said to naturally and properly belong, but also in any other manual in the instrument. It is 25 to be understood that each manual of the organ is provided with a similar set of stops, so that when one stop is operated to enable its manual to play in a certain register of pipes, the other manual may play 30 in a different register, or, by the operation of the corresponding stop, that manual may play in the same register.

To carry this object into effect, my invention comprises certain arrangements of parts coöperating with the several manuals and with a multiplex wind chest of novel construction, the same insuring greater general efficiency than has been heretofore obtained in instruments of this character, for 40 the reason that any one register may be played on one or more manuals at the same time, thereby increasing the available number of combinations and consequent variations in tone coloring, by enabling the operator to use either hand to play on one keyboard in two or more manuals while the other hand is engaged in playing other keys.

Further objects of the invention will be 50 set forth in the following specification, which is descriptive of the construction shown in the accompanying drawings, in which,—

Figure 1 represents, more or less diagrammatically, parts of a manually and automatically-operated pipe organ, the same

being in transverse section through the wind chest, the intermediate stations, the manuals, the self-playing mechanism, and the intermediate connections, said view being taken on the line 1—1 of Fig. 3. The 60 valves in the wind chest are shown in various positions of operation—the right-hand section showing the normal position. Fig. 2 represents, on a comparatively enlarged scale, one compartment of the wind 65 chest, the same being taken on a transverse section through one pipe or partition bar, and showing the two stop chambers in said bar, the valve-actuating pneumatic motors in said stop chambers, the valve for controlling the release of the pipe wind from the pipe bar, and the connections whereby the said valve may be actuated by either of said motors; and Fig. 3 is a fragmentary 70 view on the line 3—3 of Fig. 1, the same being a longitudinal section and showing one end of the wind chest, a surmounting stopbox extending transversely across the wind chest and one of the intermediate stations, the latter appearing in elevation. 75

Taking up a fuller description of the invention as shown in the drawings, and referring to the parts shown by reference characters, 1 and 2 indicate, respectively, the keys of the first and second manuals, the 80 same being operatively connected with their key valves 1^a and 2^a, said valves guarding individual ducts 1^b and 2^b, respectively, in the valve bars 1^c and 2^c, as shown. The 85 ducts 1^b and 2^b communicate directly with their respective intermediate stations 3 and 4 by way of action tubes 1^d and 2^d, for purposes well understood by those skilled 90 in the art. While it is desirable to use these sub-stations and, for certain kinds of work, 95 such stations are necessary, it will be understood that, in its broader aspect, my invention is independent of such stations.

Adjacent to the pivotal points on the key valves 1^a and 2^a, the said ducts 1^b and 2^b are 100 provided with auxiliary vents 1^e and 2^e, respectively, said vents being under control of the automatic player mechanism, indicated in Fig. 1. This automatic player mechanism comprises a spool-house 5 having a removable glass panel 5^a, which is adapted to close 105 said house so as to render the same substantially air-tight in order that the house may be filled with air under pressure. Within the spool-house is the tracker bar 5^b, the 110

same having a double line of tracker passages 5^c and 5^d, with which coöperate a perforated sheet, the same being wound from the supply-roll 5^e onto the take-up roll 5^f, all of this mechanism being of well known construction and for purposes well understood. Leading from the tracker passages 5^c and 5^d are individual action tubes 5^g and 5^h, respectively, communicating directly with a double membrane bar 6. This membrane bar is also of ordinary construction, having independent through passages 6^a and 6^b that are guarded by the individual membranes 6^e and 6^f, respectively, both of said membranes being flanked by suitable pressure chambers 6^g and 6^h, whereby the said passages may be opened or closed, depending upon the presence or absence of pressure upon one side of said membranes in the chambers 6^g or 6^h, as is usual in such cut-off devices. In direct communication with said passages 6^a and 6^b are small motor pneumatics 6^g and 6^h, respectively, the same being equipped with valves 6ⁱ and 6^j which guard the auxiliary vents 2^e and 1^e aforesaid in the valve bars 1^e and 2^e as is clearly shown in Fig. 1. Thus, it will be seen that the automatic operation of the valves 6ⁱ and 6^j is the equivalent of the manual operation of the key valves 1^a and 2^a, respectively, and that, in either event, the effect upon the intermediate stations 3 and 4 is the same. Each of the said intermediate stations is equipped with the usual primary and secondary pneumatics, and with double valves controlled thereby, said pneumatics being indicated at 7, 8 and 9 and being shown in their normal positions in station 4. When these pneumatics are vented through their communicating tubes 1^d or 2^d, as hereinbefore described, the positions of the valves are reversed, such reversed position being shown in station 3, the pneumatics in the latter station being vented by the valve 6ⁱ, which is shown in its operated position.

The intermediate stations 3 and 4 are connected to the bottom board or closure 10 for the wind chest, the said bottom board being of double construction, having two sets of independent parallel grooves or channels 10^a and 10^b, the same running transversely across said board in different horizontal planes, the grooves of the lower set 10^a communicating with intermediate station 3, and the grooves of the upper set 10^b communicating with the station 4. Surmounting said bottom board 10 are combination compartment and pipe bars 11 in parallel arrangement, said bars extending the full length and forming the partitions between the compartments of the wind chest. It will be understood that each of these pipe bars is provided with pipes comprising a register of the organ, and that each manual of the organ has a stop for causing the register of

said pipe bar to be in condition to play. It will also be understood that the operation of the same named stop or stops in the other manual or manuals will cause this same register of pipes to be played through the same pipe bar. These results are secured by the particular construction of the pipe bar, which construction will now be described.

Each bar 11 is provided with a series of angular pipe ducts 12 near its upper edge, said ducts communicating with the respective pipes of the register belonging to that pipe bar. The ducts 12 in each pipe bar open into a constant pressure compartment 13, which is formed in the wind chest between the adjacent pipe bars 11, said compartment being guarded by a pipe valve or pallet 14 that is pivotally mounted upon a rock lever 15, said lever being within the compartment and fulcrumed at 16 on the inner face of the bar having the duct 12 that is under control of the said valve. The opposite end of the rock lever 15 is felted and is adapted to cushion upon a bumper 17 on the said pipe bar. Below the lever 15 is a secondary lever 18, the same being fulcrumed at 19 on the inner face of the bar 11 and guided near its free end by a stationary pin 20, said lever being felted at its extremity and there adapted to engage the lowermost end of the lever 15, for a purpose that will hereinafter appear.

In the opposite or outer face of each compartment or pipe bar 11 are upper and lower stop channels 21 and 22, (see Fig. 2), the same extending substantially the entire length of the wind chest. These stop channels are formed within the confines of the pipe bars 11, and are bridged or inclosed by panels 23 which are securely fastened to the said bars. Each of these channels communicates through a passage or windway 24 directly with a stop-box 25, the same being of ordinary construction and preferably placed upon the top board 26 of the wind chest at one end of the latter, as shown by Figs. 1 and 3. The stop-box 25 is equipped with the usual primary and secondary pneumatic motors and coöperating double valves 27 and 28 which are under direct control of the stop-knobs, said knobs, as is usual, being arranged adjacent the key board of the organ.

As appears from Fig. 1, each pipe bar 11 has two sets of pneumatic motors and valves in the stop-box, the numbers of such sets for each bar depending upon the number of manuals in the organ. It will be understood, therefore, that if the organ be furnished with three, four or more manuals, a corresponding number of sets of such motors and valves will be provided in the stop-box for each pipe-bar, and each set will control its respective stop channel in said bar. The drawings showing two of such sets, the 130

motors in the set controlling the stop chamber 22 are designated 28 and 27, while the corresponding sets controlling the stop channels 21 are designated 280 and 270.

5 With the motor 28 shown in Fig. 3, the same appearing near the right-hand end of Fig. 1, there is connected a tube 28^a, the same leading to a valve bar 28^b that is located adjacent the manuals. This valve bar has an 10 air passage 28^c therein and leading outwardly, the outer end of said passage being controlled by a valve 28^d. The valve is lifted by a stop-knob 28^e that is suitably guided in stationary parts of the organ, said knob 15 having a cam 28^f that co-operates with a similar cam 28^g on the valve so that, when the knob is drawn, the valve is lifted, the pressure released in the tube 28^c the motor 28 corresponding thereto operates, and the stop-channel 22 is vented. In a similar manner, 20 and through corresponding connections, the motor 280 is deflated when the stop-knob 280^e is drawn, such action resulting in venting the stop-channel 21. The stop-knobs 28^e and 280^e bear, of course, the same 25 label or caption, since they control the same pipe bar, 11. From this it follows that any register of pipes may be played from either manual; and, as will hereinafter appear, the 30 same register of pipes may be played at one time from all of the manuals for which a stop corresponding to that pipe bar has now operated.

Within each of the stop channels 21 and 35 22, and within the confines of each bar 11, is located a series or set of pneumatic motors 29 and 30, respectively, there being one set of motors for each manual, either of which motors may, at the will of the operator, be 40 caused to unseat the corresponding valve pallet 14. These valve-actuating pneumatic motors are, by preference, rectangular in form, having raised ends and a depressed base that is secured directly to the pipe bars, 45 and each base is perforated centrally at 31 so as to form a feed hole that communicates directly with its respective supply duct 32 or 33 that leads to the grooves 10^a or 10^b in the bottom board of the wind chest. The 50 motors 29 and 30 are each further provided with a membranous air-tight covering 34, upon the outside of which is a non-flexible reinforcing plate 35. Upon the inside of the membranous cover 34 there is centrally secured a padded pallet 36 that serves the 55 double purpose of insuring a silent return of the motor pneumatic to its seated or normal position after each vibration and of covering or packing the supply duct to guard against 60 and effectually prevent leakage from the stop channel through the membranous cover 34 into said supply duct. Projecting inwardly from each of said pneumatic motors 29 and 30, through the corresponding pipe bar 11, 65 are pull wires 37 and 38, respectively, the

wire 37 being secured to the rock lever 15 and the wire 38 being secured to the secondary lever 18, as best shown by Fig. 2.

While, as stated, the drawings show an organ having but two manuals, in which case but two stop channels with their contained pneumatics and their corresponding levers is provided, it will be understood that additional manuals and corresponding additional stop channels may be provided, in which case the additional stop channels would each have its corresponding series or set of pneumatic motors which would be connected to a series of levers corresponding to the levers 18 but being adapted, upon 70 operation, to compress all of the levers 18 and 15 co-operating therewith, so that the same register of pipes may be played from any one or all of the manuals.

75 The foregoing being a description of my invention in one practical form of construction, its use and leading points of advantage will now be briefly set forth.

80 It being assumed that the interior of the spool-house 5, the intermediate stations 3 and 4, all of the compartments 13, all of the stop channels 21 and 22 and the stop-box 25 are normally charged with pipe wind under suitable pressures from a source of supply, not shown; that all key valves 1^a and 1^b and 85 all automatic valves 6ⁱ and 6^j are seated, like those appearing in connection with the second manual; that all pneumatics and valves 7, 8 and 9 of both intermediate stations 3 and 4 occupy positions as indicated in the 90 intermediate station 4, and that all the motor pneumatics 29 and 30 are deflated, as indicated in Fig. 2 of the present drawings, then the withdrawal of any stop-knob 28^e in the set of stop-knobs belonging to the second 95 manual operates, through the stop-box 25, to vent the corresponding stop channel 22 and to thus render the corresponding register of pipes available. Depression of any 100 particular key in the second organ manual 100 results in lifting the corresponding key valve 2^a and in venting the corresponding duct 2^b, with the effect of reversing the position of the pneumatic valves 7, 8 and 9 belonging to that key in station 4. This 105 instantly charges the corresponding communicating groove 10^b of bottom board 10, as well as its lateral supply ducts 33 in communication with the interior of all pneumatic motors 30 communicating with that 110 groove, that motor 30 that corresponds to the key depressed and is located in the stop channel 22 from which the pressure has been relieved, being inflated, while the motors 30 in the remaining stop channels connected 115 with said groove remain deflated owing to the fact that the pressure in their stop channels has not been relieved. Such inflation of the pneumatic motor 30 instantly operates upon the secondary lever 18 and rock 120 125

130

lever 15 to unseat the corresponding pipe valve 14, whereupon the inrush of pipe wind from compartment 13 instantly causes the corresponding pipe to speak.

5 Assuming now that the corresponding stop knob belonging to the first manual be drawn, the corresponding stop chamber 21 is relieved of its pressure so that the depression of a key in the first manual, operating through the intermediate station 3 and the corresponding groove 10^a, operates to inflate the pneumatic motor 29 corresponding to the depressed key and to open the same valve 14 so as to cause the same organ pipe 15 to speak. Thus, it will be particularly noted that any individual pipe belonging to any predetermined register of pipes may be controlled directly from its corresponding key upon the first organ manual or may be similarly controlled from the corresponding key 20 of the second organ manual when the corresponding stop belonging to the second manual is drawn, whereby all the advantages of a multiplex wind chest are obtained in a most effective and simple manner. It will also be noted that the structural arrangement and combination of parts hereinbefore described results in a very compact structure, and in a material economy of space, 30 this oftentimes being a factor of the greatest importance in organ construction. Moreover, as has been set forth, by mere multiplication of the component parts hereinbefore described, other organ manuals and 35 their corresponding mechanisms may be added without increasing the width of the wind chest.

Attention should also be particularly directed to the aforesaid construction and resulting action of the valve-actuating motor pneumatics 29 and 30. It being assumed that a stop has been drawn, each depression of a manual key causes the corresponding motor controlled by that stop to be first inflated and then, upon the release of the key, 45 to be instantly returned to its normal collapsed position, as best shown by Fig. 2 of the drawings. During its inflating movement, the outer reinforcing plate 35 insures an even motion within the comparatively limited space of its particular stop channel without the possibility of undue outward bulging at the center of the motor, while, during the second or collapsing movement, 50 said motor is cushioned upon a padded pallet 36 for the two-fold purpose of insuring silence and of effectually closing its valve duct 31 to prevent the possibility of leakage from the normally-charged stop channel 55 through the membranous motor cover to the supply duct leading to the grooved bottom board.

The action hereinbefore described in connection with the manual operation is clearly 60 suited to automatic control as shown in the

drawings, practically the only difference being the manner of venting the intermediate stations 3 and 4 through their respective valve bars 1^c and 2^c. A perforated music roll having been introduced into the spool-house 5 through the panel 5^a, or other suitable closure, the normal pressure within the housing may be automatically admitted by the act of closing the said panel, as is usual in structures of this character when 70 acting under pressure as distinguished from an exhaust system. Free passage of the wind through membrane bars 6 is now established, as usual, by touch of a suitable piston or switch, not shown, at the keyboard of the instrument, and a consequent relieving of the pressure from behind membranes 6^c and 6^d. Thereupon, the registration of a note perforation or perforations in the note sheet with its appropriate passage or 75 passages in the tracker bar 5^b, instantly results in inflating, through action tubes 5^e and 5^f, the corresponding miniature pneumatics 6^e, 6^f, whereby their valve pallets 6^g and 6^h are lifted and the corresponding intermediate stations are vented, as described in connection with the manuals.

Having thus described my invention, what I claim is:

1. In a musical instrument, the combination with a plurality of manuals, of a register of musical pipes, a pipe bar having a series of ducts therein, there being one duct for and communicating with each pipe of the register, a valve for each duct controlling the air communication to its respective pipe, a series of channels in said pipe bar, there being one of said channels for each manual, a pneumatic motor in each channel for each of the said valves, means connected with each of said motors for operating its respective valve, a stop box, and means controlling said box, whereby one or more of said channels may be vented to permit the motors therein to operate upon the depression of the corresponding keys in the corresponding manuals.

2. In a pipe organ the combination of a plurality of organ divisions, a wind-chest having pipe-wind compartments, pipe bars forming the opposite walls of said compartments, an independent channel in each pipe bar for each organ division, a stop box for exhausting said channels, a pneumatic motor for each pipe in each of said channels, a valve for each pipe, and means for controlling each of said valves from either of said motors, substantially as described.

3. In a pipe organ the combination of a plurality of organ divisions, a wind-chest having pipe-wind compartments, pipe bars forming the opposite walls of said compartments, an independent channel in each pipe bar for each organ division, a pneumatic motor for each pipe in each of said chan- 130

- nels, a valve for each pipe, and a system of levers for controlling each of said valves from either of said motors, substantially as described.
5. In a pipe organ, the combination, with a plurality of organ divisions, of automatic player mechanism for operating any or all of these divisions, a wind chest having pipe wind compartments, pipe bars forming the 10 opposite walls of said compartments, an independent channel in each pipe bar for each organ division, a stop box for venting said channels, a pneumatic motor for each pipe in each of said channels, a valve for each pipe, and means for controlling each of said valves from any of said motors.
5. In a pipe organ, the combination, with a plurality of manuals, of pipe bars having a plurality of channels therein, means in 20 each channel for speaking each organ pipe of the pipe bar, and stops venting these channels whereby the corresponding manual may play the organ pipe of this pipe bar.
6. In a pipe organ, the combination, with 25 a plurality of manuals, of pipe bars, an in-
- dependent channel in each pipe bar for each manual, a stop box for venting said channels, a pneumatic motor for each pipe in each of said channels, a valve for each pipe, and means for controlling each of said valves 30 for either of said motors related thereto.
7. In a pipe organ, the combination, with a plurality of manuals, of pipe bars, an independent channel in each pipe bar for each manual, sets of stops associated with 35 the respective manuals, means controlled thereby for venting said channels respectively, a pneumatic motor for each pipe in each of said channels, a valve for each pipe, and means for controlling each of said 40 valves for either of said motors related thereto.

In testimony whereof, I hereunto affix my signature in the presence of two witnesses.

PHILIPP WIRSCHING.
